United States Patent Office

Des. 188,732
Patented Aug. 30, 1960

188,732

KEY CONTAINER

Raymond E. Morman, 210 S. Ervay St., Dallas, Tex.

Filed Oct. 1, 1959, Ser. No. 57,757

Term of patent 7 years

(Cl. D87—3)

Figure 1 is an exploded perspective view of a key container showing my new design;

Figure 2 is a top plan view;

Figure 3 is a front elevational view; and

Figure 4 is a rear elevational view.

A portion of a key is shown in broken lines in Figure 1 for purposes of illustration.

I claim:

The ornamental design for a key container, substantially as shown and described.
